UNITED STATES PATENT OFFICE.

BRUNO ZABEL, OF PITTSBURGH, PENNSYLVANIA, ASSIGNOR TO TOSCA ZABEL, OF FEURA BUSH, NEW YORK.

MECHANICAL TOY.

Application filed November 25, 1924. Serial No. 752,168.

This invention is for a mechanical toy of the type in which a gravity propelled object is guided alternately from one end of the track to the other by a rocking movement of 5 the track, and caused to "loop-the-loop" during such travel.

The present invention has for its principal object to provide a practical mechanical loop-the-loop toy wherein the "action" is 10 entirely automatic.

A further object of the invention is to provide a mechanical toy having a looped track and a novel means for supporting and rocking the track.

15 Further objects of the invention are to provide a toy so timed as to ensure the proper action of the gravity propelled object, and to provide a toy which may be cheaply manufactured and compactly packed.

20 These and other objects and advantages may be attained by my invention, which may be readily understood by reference to the accompanying drawings, in which:

Fig. 1 is a side elevation of a toy constructed in accordance with my invention;

Fig. 2 is a plan view thereof;

Fig. 3 is a diagrammatic view, illustrating the position of parts at the beginning of a cycle of movements of the car or gravity 30 propelled object;

Fig. 4 is a similar view indicating the position of parts just after the car has made the loop;

Fig. 5 is a similar view illustrating still 35 another position in which one end of the track is in its lowermost position and the other end highest; and

Fig. 6 is a detail view of the pivotal suspension for the track; Fig. 7 is a detail view 40 of a slight modification.

In the drawings, 5 designates a suitable base of sheet metal or other suitable material. Secured to the base is a suitable track supporting frame or bracket, preferably in the 45 form of a curved flanged strip 6 having a widened upper end 7 from which depend ears 8.

Passing through these ears and through 50 upright lugs 9 on a cross strip 10 secured to the top of the loop 11 of the track, is a pin 12. The track is preferably made of channeled sheet metal and comprises a single central loop 11, which is necessarily helical, having tangential bottom extensions 11a. The 55 outer ends of the extensions, which project

upwardly at an angle to the horizontal, are preferably detachably connected at 13 with the position of the track forming the loop, the extensions being designated as 14. The type of joint may be similar to that shown in my United States Patent No. 1,469,710, dated October 2, 1923. At the outer free ends of the track sections 14 are upright stops 15. A large part of the inner area of the tracks is punched out to make them as light as 65 possible.

While the major length of the extensions 14 is, when the loop is in a central position, as shown in Fig. 1, angular to the horizontal, the outer end portions 14a are substantially 70 horizontal. When the track is rocked, as it may rock on pin 12 to lower one end of the track and raise the other, the portion 14a on the higher end will incline toward the loop, as shown in Figs. 3, 4 and 5, while the 75 portion 14a at the lower end will slope away from the loop. This is important. The track is substantially balanced on the pin 12.

Mounted on the base is a suitable motor, such as spring motor 16, having a crank or 80 eccentric pin 17 driven thereby. A link 19 connects eccentric pin or crank 17 with the track at a point directly below the pivot point for the track. A post 18 may be provided to which the link connects, this post 85 being carried on cross piece 18a.

When the crank revolves, it serves to rock the balanced track through post 18 and link 19. When the crank is in vertical alignment, up or down, with its center of rotation, the track is in the balanced central position of Fig. 1. When the crank is in the horizontal position toward the loop, one end of the track is in its highest position and the other end in its lowest position, as shown 90 for instance in Fig. 5. When it is in a diametrically opposite position, the high and low ends are reversed.

Mounted for movement in the track is a gravity propelled object, such as a car A, 100 which is preferably very light and very free running, and of a width leaving plenty of freedom between its wheels and the side flanges of the track.

In operation, assume that one end X, at 105 which the car is situated, is moved by the motor or other operating means slightly above the position in which its track portion 14a is horizontal. The car A immediately starts rolling down the incline, and as the 110

car rolls down, the track continues to move up, increasing its angularity with respect to the horizontal. At the same time, the opposite end Y is moving toward the horizontal. 5 If the track stopped moving just as the car started down the incline, it would not have sufficient velocity, after making the loop, to climb the other end Y of the track. As the passage of the car around the loop requires 10 but an instant, it will be found that the end Y will still be lowering after it has passed the loop. While the momentum of the car is decreasing, the angle of its climb decreases. Just as end X reaches its highest point, the 15 car will come to rest on portion 14^a of the lower end Y. At this time, end Y will begin to rise, but, since portion 14^a is inclined away from the loop until the track is in or slightly past the central position of 20 Fig. 1, the car will not roll toward the loop until end Y starts to move higher than end X. Then the car will travel from end Y to end X in the same fashion as from X to Y.

By changing the angle of portion 14^a with 25 respect to the main slope of the sections 14, the cars could be retained on the rising end for a longer period of time, but if this were done to any substantial extent, it would be found that the lower end of the track would 30 be rising before the car, with its decreasing momentum, reached the end.

The manner of suspending the looped track and of rocking it from a point at the bottom of the loop requires minimum power 35 to rock it, so that a light, cheap, motor may be successfully used. It also provides an extremely strong and durable construction, and provides a construction wherein the range of movement necessary to rock the 40 track can be conveniently attained. It further provides a movement of the loop wherein the bottom of the loop is shifted longitudinally from one extreme to the other while the top of the loop is fixed 45 against longitudinal shifting. This is important in giving the track the proper movement to cause the car to travel back and forth in the manner described. The manner of operating the toy through the link connection and eccentric also adds to the "action" or attractiveness, from a mechanical 50 standpoint, of the toy.

Instead of having a post 18, the link may connect directly to the cross-piece 18^a connecting the two ends of the loop at the bottom, as shown in Fig. 7.

Various changes and modifications may be made in the construction within the contemplation of the invention and under the 60 scope of the appended claims, it being understood that the form particularly shown and described is merely illustrative of a preferred embodiment of the invention.

What I claim is:

1. A mechanical toy including a vertically

looped track, a pivotal suspension for the track at the top of the loop, means for rocking the track, and a gravity propelled object on the track.

2. A mechanical toy including a base, a bracket on the base having an overhung upper end, a looped track having a central loop and inclined extensions on each side of the loop, means at the top of the loop pivotally suspended from the bracket for supporting the track, a motor on the base, an eccentric driven by the motor, means connecting the eccentric with the track for rocking the same, and a gravity propelled object on the track. 70

3. A mechanical toy including a base, a bracket on the base having an overhung upper end, a looped track having a central loop and inclined extensions on each side of the loop, means at the top of the loop pivotally suspended from the bracket for supporting the track, a motor on the base, an eccentric driven by the motor, means connecting the eccentric with the track at the center of the loop directly below its point of suspension for rocking the same, and a gravity propelled object on the track. 75

4. A mechanical toy including a pivotally supported track comprising a central loop and inclined extensions, car-receiving terminals at each end of the track, a gravity propelled car on the track, a motor, and means for transmitting a rocking movement from the motor to the track to impart a continuous oscillating movement thereto, said terminals being angularly disposed to the main slope of the inclined extension in such manner as to be horizontal substantially midway between the upper and lower limits of rocking movement of the track. 90

5. A mechanical toy having a vertically looped track with inclined extensions at each side of the looped portion, means for moving the bottom of the loop back and forth in the direction of the length of the track, said support maintaining the upper part of the loop in a substantially fixed position. 100

6. A mechanical toy including a base, a curved bracket on the base having an upper end overhanging the base, a track having inclined extensions and a central loop, which loop is partially disposed under the curved bracket, means at the top of the loop for pivotally suspending it from the bracket, whereby it may rock in a vertical plane, a motor on the base, an eccentric driven by the motor, and a link connecting the eccentric with the track, said eccentric and link serving to transmit a rocking movement to the track, the inclined extensions of the track forming substantially equal angles to the horizontal when the eccentric is in vertical alinement with its center of rotation. 110

In testimony whereof I affix my signature.
BRUNO ZABEL.
